UNITED STATES PATENT OFFICE.

ALEXANDER D. FERGUSON, OF MICHIGAN CITY, INDIANA, ASSIGNOR TO SULLIVAN MACHINERY COMPANY, A CORPORATION OF MASSACHUSETTS.

TONGS.

Application filed December 14, 1926. Serial No. 154,818.

This invention relates to tongs and more particularly to improved "spinning" tongs for breaking and spinning tool joints.

An object of this invention is to provide an improved tong. Another object of this invention is to provide an improved tong whereby the drill rod joints may be broken and the rod thereafter given a spinning or rapid rotative movement to completely uncouple the joint. Yet another object of this invention is to provide an improved breaking and spinning tong for drill rod joints having improved mechanism for gripping the drill rods and for imparting a rapid spinning movement to the rod to completely release the joint. Still another object of this invention is to provide an improved breaking and spinning tong which is connected to the well derrick and to the cat-line from the power driven cat-head of the drilling apparatus. Another object of this invention is to provide an improved power operated tong for making and breaking out or unscrewing tool joints. These and other objects and advantages of the invention will, however, hereinafter more fully appear.

In the accompanying drawings there is shown for purposes of illustration one form which the invention may assume in practice.

In these drawings,—

30 Fig. 1 is a plan view of the improved tong.

Fig. 2 is a central longitudinally extending vertical sectional view taken substantially on line 2—2 of Fig. 1, parts being shown in elevation.

35 Fig. 3 is a detail view illustrating clamping or gripping jaws and actuating means therefor.

Fig. 4 is a detail sectional view, taken in a plane corresponding to the plane of Fig. 2, 40 illustrating a portion of the improved spinning mechanism.

Fig. 5 is a detail sectional view taken on line 5—5 of Fig. 1.

45 Fig. 6 is a diagrammatic view illustrating the different operative positions of the tong when breaking a tool joint.

In this illustrative embodiment of the invention there is shown an improved breaking and spinning tong generally designated 1 and 50 comprising a body or casing 2 having formed integral therewith a radially extending hollow arm or lever 3. A detachable cover plate 4 is provided to permit access to the internal mechanism of the tong and this plate is secured by screws 5 to the casing 2. Preferably

formed integral with the frame 2 is a stationary jaw 6, while pivoted at the outer end of this jaw, at 7, is a jaw 8. Jaws 9 and 10 are also provided pivoted together at 11. As clearly shown in Fig. 3 the jaw 9 has pivoted thereto, as at 12, a spring pressed latch 13 adapted to engage a projecting lug 14 formed on the jaw 8, thereby connecting the adjacent ends of the jaws 8 and 9 together. A handle or grasping portion 15 is formed on the latch to facilitate manual release thereof. Carried by each of the jaws 6, 8, 9, and 10 are vertical pins 16 (see Fig. 5) on which spaced aligned roller bearings 17 are mounted, these bearings being disposed within recesses 18 formed in the jaws. Disposed within the jaws and rotatably mounted on the bearings 17 are gripping devices comprising gear segments 19 having internal serrations or teeth 19^a the purpose of which will be later described. The gear segments 19 of the gripping devices have at the lower end thereof internal grooves 20 with which inwardly projecting flanges 21 on the jaws interlock, thereby preventing displacement of the gear segments therefrom. The jaws 6, 8, 9, and 10 are so constructed that they may accommodate several different sizes of gripping jaws to compensate for the different diameters of rods, casing, or pipe to be uncoupled. Again referring to Fig. 3 55 it will be observed that the jaw 10 is pivotally connected as at 22 to one arm, herein the shorter arm, of a bell-crank 23 pivoted, as at 24, on the frame 2. The bell-crank 23 is housed within the frame 2, a lateral recess being provided in the frame to permit swinging movement of the bell-crank about its pivot. In this instance one of the arms of the bell-crank 23 is elongated and carries at its extremity a guide roll or sheave 25 rotatably mounted on a vertical pin 26 carried by the arm. The bell-crank 23 is adapted to be swung about its pivot to cause the jaws 8, 9, and 10 to move inwardly, thereby gripping the drill rod in a manner to be later described.

As clearly shown in Fig. 2 the rotatable gear segments 19 cooperate to form a complete gear, having meshing therewith a larger spur gear 27 rotatably mounted on the outer race of a roller bearing 28 having an inner race surrounding and supported by a stationary vertical shaft 29. The lower end of the shaft 29 is suitably fixed to the casing 2 while the upper end of the shaft is supported by the cover plate 4. Interposed between the

110

upper surface of the hub of the gear 27 and the cover plate 4 is a ball thrust bearing 30 which receives the upward thrust of the gear 27. Furthermore, disposed below and 5 axial with the gear 27 and rotatably mounted on the outer race of a roller bearing 31 having an inner race supported by the shaft 29 is a winding drum 32 having formed thereon on the upper surface thereof ratchet teeth 33 which engage corresponding ratchet teeth 34 formed on the lower surface of the spur gear 27. The ratchet teeth 33 on the drum are resiliently or yieldably held into engagement with the ratchet teeth 34 on the gear 27 by 10 means of a coiled spring 35 encircling the shaft 29 and interposed between the bottom of the casing 2 and a flanged sleeve 36 keyed to and slidably axially on the stationary shaft 29. Interposed between the flanged portion 15 of the non-rotatable sleeve 36 and the bottom cover plate 37 secured to the rotatable drum 32 is a ball thrust bearing 38. It will be obvious that the gear 27 and drum 32 rotate together in one direction but when the drum 20 rotates in the opposite direction the ratchet teeth 33 slip over the ratchet teeth 34 thereby permitting the drum to rotate relative to the gear. Secured to the non-rotatable sleeve 36 at one end thereof and to the drum 32 at the 25 other end thereof is a flat spiral spring 39 and this spring always tends to cause the drum 32 to wind in a flat wire cable 40 thereon, the latter being suitably secured to the drum at one end thereof. The cable 40 extends from 30 the drum 32 around the guide roll 25 on the bell crank 23 and longitudinally outwardly through the hollow portion of the arm 3 and around a guide roll or sheave 41 rotatably mounted on a vertical pin 42 carried by the 35 arm, the free outer end of this cable 40 having attached thereto an eye member 43. As shown in the drawings the cover plate 4 of the frame is provided with a slot or groove 44 within which is reciprocably mounted a dog 40 or plunger 45. This dog 45 is normally forced inwardly by a spring 46 into locking engagement with one of a plurality of recesses 47 formed in the hub of the gear 27 and consequently the gear 27 is held against rotation 45 relative to the frame 2. Suitably secured to the dog 45 and extending outwardly through the hollow arm 3 is a cable 48 which extends around a guide roll or sheave 49 rotatably mounted on a vertical pin 50 carried by the 50 arm. The cable 48 has secured thereto at its free end an eye member 51.

In the operation of the improved breaking and spinning tong the latter is supported in the usual manner by a cable suspended from 55 the derrick. The jaws 8 and 9 are swung open at this time, the latch 13 being released and the tong is suitably positioned relative to the drill rod. The jaws are then swung inwardly to embrace the rod and locked in this position by means of the latch 13. The eye mem- 60 ber 43 on the cable 40 is then suitably connected to the cat-line 52 which is wound on the usual cat-head 53 of the drilling apparatus 54 as clearly shown in Fig. 6. The cable 48 is connected to the derrick post 55 of the 70 derrick. A coiled spring 56 is connected to the cable 48 and this spring takes up the slack in the cable when the tong is in the dotted line position shown in Fig. 6. The cat-head 53 is then connected to the drill engine and the line 75 is wound in by power, thereby causing the cable 40 to become taut. Consequently the bell-crank 23 is swung about its pivot 24 from the full line position shown in Fig. 3 to the dotted line position and consequently the jaws are moved inwardly, thereby gripping the drill rod. As the cable 40 is wound in by the cat-head 53 the spinning tong is swung from the dotted line position shown in Fig. 6 to the 80 full line position, thereby breaking the drill rod joint. As the joint is broken and upon swinging movement of the tong the slack in the cable 48 is taken up and the dog 45 is then automatically released from the recess 47. Upon release of the dog the gear 27 is disconnected from the frame 2 and the cable 40 is rapidly unwound from the drum 32 and due to the connection of the ratchet teeth 33, 34 between the drum and gear 27 the latter is also 85 rapidly rotated. As this gear meshes with the gear formed by the gear segments 19 of the gripping devices the latter are rapidly rotated and as they grip the drill rod the latter is rapidly rotated therewith and consequently the joint is completely unthreaded. 90 It will thus be evident that the drill rod is initially gripped and relatively slowly rotated to break the joint by the swinging movement of the tong lever 3 and thereafter the joint is completely uncoupled by the relatively rapid 95 spinning action automatically imparted to the rod independently of further swinging movement of the tong lever. As the drum 32 rotates during the spinning operation the spring 39 will wind up tightly and when the cat-line 52 and cable 40 are slackened this 100 spring will cause the drum to rewind the cable 40, the ratchet teeth 33 on the drum slipping over the ratchet teeth 34 on the gear 27 at that time. The uncoupled drill rod will 105 be supported by the tong which is held suspended from the derrick in the usual manner and upon release of the latch 13 the jaws may be opened to release the jaws from the rod. 110 This single operation should be enough to disconnect the joint entirely. However, in handling rods having unusually long threads this operation may be repeated by slackening the cat-line 52 and the tong will automatically 115 return from the full line position to the dotted line position in Fig. 6 by the means of the coiled spring 56. The cat-line 52 may then again be wound in and the spinning operation described above is repeated until the 120 joint is completely unthreaded. The im- 125 130

proved tong may also be used to make or thread joints in an obvious manner.

- As a result of this invention it will be noted that an improved tong is provided by means of which the breaking and spinning of tool joints may be facilitated and the time consumed reduced to a minimum. It will further be noted that an improved breaking and spinning tong is provided which may be used 10 in the same manner as an ordinary breaking tong and which may be subjected to the same hard usage encountered in drilling work. It will further be noted that the improved breaking and spinning tong is of simple and 15 compact construction, the improved tong being substantially no larger than the usual tong which has no spinning function. These and other advantages of this invention will be clearly apparent to those skilled in this art.
- 20 While I have in this application specifically described one form which my invention may assume in practice, it will be understood that the same has been shown for purposes of illustration and that the invention may be modified and embodied in various other forms 25 without departing from its spirit or the scope of the appended claims.

What I claim as new and desire to secure by Letters Patent is:

- 30 1. A device for uncoupling drill rod joints comprising power operated means for initially breaking the joint and means for thereafter automatically imparting a spinning movement to the rod to completely uncouple the joint. 35 2. A device for uncoupling drill rod joints comprising power operated means for breaking the joint, means for thereafter imparting a spinning movement to the drill rod to completely uncouple the joint, and means for automatically returning said latter means to its initial position after the joint is uncoupled. 40 3. A device for uncoupling drill rod joints comprising means for initially gripping and relatively slowly rotating the drill rod for breaking the joint, and means for thereafter automatically imparting a relatively rapid spinning movement to the drill rod to completely uncouple the joint. 45 4. A device for uncoupling drill rod joints comprising means for initially gripping and relatively slowly rotating the drill rod for breaking the joint, and means for thereafter automatically imparting a relatively rapid spinning movement to the drill rod to completely uncouple the joint, said gripping means being operated by said spinning means. 50 5. A device for uncoupling drill rod joints comprising means for initially breaking the joint and means associated with said joint breaking means for thereafter automatically imparting a spinning movement to the rod to completely uncouple the joint. 55 6. A device for uncoupling drill rod joints comprising a casing including an elongated hollow arm, means for gripping the drill rod comprising jaws pivotally mounted on said casing, means for actuating said jaws including a cable extending through said hollow arm, and means for guiding said cable mounted on the outer extremity of said arm. 70 7. A device for uncoupling drill rod joints comprising a casing including an elongated hollow arm, means for gripping the drill rod comprising jaws pivotally mounted on said casing, means for actuating said jaws including a cable extending through said hollow arm and a bell crank operated by said cable and pivotally connected to one of said jaws, 75 and means for guiding said cable mounted on the outer extremity of said arm. 80 8. A device for uncoupling drill rod joints comprising a casing having a projecting arm thereon, means for gripping the drill rod comprising jaws pivotally mounted on said casing, and means for actuating said jaws comprising a cable and means cooperating with said cable and movable when tension is applied thereto. 85 9. A device for uncoupling drill rod joints comprising a casing, drill rod gripping jaws pivotally mounted on said casing, a drum rotatably mounted within said casing, a cable on said drum, and means cooperating with 90 said cable for actuating said jaws to grip the drill rod when tension is applied to said cable. 95 10. A device for uncoupling drill rod joints comprising a casing, drill rod gripping jaws pivotally mounted on said casing, a drum rotatably mounted within said casing, a cable on said drum, and means cooperating with 100 said cable for actuating said jaws to grip the drill rod when tension is applied to said cable, and means for automatically rotating said drum to wind in said cable when said tension on said cable is released. 105 11. A device for uncoupling drill rod joints comprising a tong adapted to grip the drill rod and having a portion forming a lever arm adapted to be swung to break the joint, and means for automatically imparting a spinning movement to the rod to completely uncouple the joint independently of 110 further swinging movement of said lever arm. 115 12. A device for uncoupling drill rod joints comprising a tong adapted to grip the drill rod and having a portion forming a lever arm adapted to be swung to break the joint, and means automatically releasable upon a predetermined swinging movement of 120 said tong for imparting a spinning movement to the drill rod independently of further swinging movement of said lever arm. 125 13. A device for uncoupling drill rod joints comprising a tong adapted to grip a drill rod and including a lever adapted to be swung to rotate the rod to break the joint, 130

and means for rotating the rod independently of further swinging movement of said lever.

14. A device for uncoupling drill rod joints comprising a tong, power operated means for causing the tong to grip a drill rod and including a lever for swinging the tong to rotate the rod to break the joint, and means automatically releasable upon a predetermined swinging movement of the tong to impart a spinning movement to the rod independently of further swinging movement of said lever.

15. In a tong, a casing having a laterally projecting arm, drill rod gripping jaws pivotally mounted on said casing, means carried by said casing for actuating said jaws to cause the latter to grip the drill rod including a flexible element, and means carried at the extremity of said arm for guiding said element, said flexible element also being adapted to swing said tong.

16. A device for uncoupling drill rod joints comprising a tong adapted to grip a rod and having a lever arm adapted to be swung to break the joint, and means automatically operative after a predetermined swinging movement of said lever arm for rotating the rod independently of further swinging movement of said lever arm.

17. In a tong, a casing having a laterally projecting lever portion, gripping jaws pivotally mounted on said casing, power operated means for actuating said jaws comprising a bell-crank pivotally mounted on said casing and having an arm thereof pivotally connected to one of said jaws, the other arm thereof carrying a guide roll, a flexible element guided by said roll for actuating said bell crank, said flexible element extending outwardly along said lever portion, and a guiding roll carried by the extremity of said lever portion for guiding said flexible element.

18. In a tong, a casing, jaws pivotally mounted on said casing, rotatable gripping devices carried by said jaws and journaled thereon, means carried by said casing for actuating said jaws, and means carried by said casing and cooperating with said jaw actuating means for effecting rotation of said gripping devices bodily relative to said jaws.

19. In a tong, a casing, jaws pivotally mounted thereon, gripping devices rotatably mounted on said jaws, means for effecting rotation of said gripping devices relative to said jaws comprising a drum rotatably mounted on said casing, a cable wound on said drum, said drum rotating when said cable is unwound therefrom, and operative connections between said drum and gripping devices for transmitting drum rotation thereto.

20. In a tong, a casing, jaws pivotally mounted thereon, gripping devices rotatably

mounted on said jaws, means for effecting rotation of said gripping devices relative to said jaws including a drum rotatably mounted on said casing, and a cable wound on said drum, and means for actuating said jaws including means cooperating with said cable and operated when tension is applied to said cable.

21. In a tong, a casing, jaws pivotally mounted thereon, gripping devices rotatably mounted on said jaws, said gripping devices including gear segments, means for effecting rotation of said gripping devices including a gear meshing with said gear segments, a drum connected to said gear to effect rotation thereof, and a cable wound on said drum for rotating the latter.

22. In a tong, a casing, jaws pivotally mounted thereon, gripping devices rotatably mounted on said jaws and including gear segments, means for effecting rotation of said gripping devices relative to said jaws comprising a gear meshing with said gear segments, a winding drum disposed coaxial with said gear and rotatably mounted on said casing, cooperating ratchet teeth on said drum and gear, a spring for forcing said ratchet teeth on said drum into engagement with the ratchet teeth on said gear whereby said gear and drum may rotate together in one direction and said drum may rotate relative to said gear in the opposite direction, and a cable wound on said drum for rotating the latter.

23. In a tong, a casing, jaws pivotally mounted thereon, gripping devices rotatably mounted on said jaws and including gear segments, means for effecting rotation of said gripping devices relative to said jaws comprising a gear meshing with said gear segments, a winding drum disposed coaxial with said gear and rotatably mounted on said casing, cooperating ratchet teeth on said drum and gear, a spring for forcing said ratchet teeth on said drum into engagement with the ratchet teeth on said gear whereby said gear and drum may rotate together in one direction and said drum may rotate relative to said gear in the opposite direction, and a cable wound on said drum, and means for actuating said jaws comprising a bell-crank pivotally mounted on said casing and having an arm thereof pivotally connected to one of said jaws, the other arm thereof carrying a guiding roll engaging said cable, said bell-crank being actuated when tension is applied to said cable.

24. In a tong, a casing, jaws pivotally mounted thereon, gripping devices rotatably mounted on said jaws and including gear segments, means for effecting rotation of said gripping devices relative to said jaws comprising a gear meshing with said gear segments, a winding drum disposed coaxial with said gear and rotatably mounted on said cas-

ing, cooperating ratchet teeth on said drum and gear, a spring for forcing said ratchet teeth on said drum into engagement with the ratchet teeth on said gear whereby said gear and drum may rotate together in one direction and said drum may rotate relative to said gear in the opposite direction, and a cable wound on said drum, means for actuating said jaws comprising a bell-crank pivotally mounted on said casing and having an arm

thereof pivotally connected to one of said jaws, the other arm thereof carrying a guiding roll engaging said cable, said bell-crank being actuated when tension is applied to said cable, and means for automatically winding 15 the cable on said drum when tension on said cable is released.

In testimony whereof I affix my signature.

ALEXANDER D. FERGUSON.
